UNITED STATES PATENT OFFICE.

JOHN C. BRIGHTON, OF ASBURY PARK, NEW JERSEY.

FIRE ESCAPE.

Application filed December 2, 1925. Serial No. 72,793.

This invention relates to fire escapes and more particularly to a fire escape intended for use in apartments and other buildings which would be disfigured by fire escapes 5 erected externally of the building.

One object of the invention is to provide a fire escape in the form of a ladder adapted to be stored in a small box-like receptacle which will be neat in appearance and may 10 be disposed upon the floor of a room adjacent a window without being unsightly.

Another object of the invention is to so 15 construct the ladder that when the cover is removed from the receptacle the ladder may be readily removed and passed out of the window so that an occupant of the room may climb down the ladder and escape if a hall with which the room communicates is im- 20 passable due to the presence of flame or smoke.

Another object of the invention is to provide enlarged eyes at the ends of the rungs which not only serve to connect the rungs with the side chains but also constitute means 25 to hold the rungs in spaced relation to the wall of the building and prevent the fingers from being mashed and permit the feet to readily engage the rungs.

Another object of the invention is to so 30 construct the ladder that it will be very strong and not liable to break when supporting the weight of a number of persons.

This invention is illustrated in the accompanying drawing, wherein

35 Figure 1 is a view showing a fragment of a room with the fire escape provided therein;

Fig. 2 is an enlarged sectional view taken on the line 2—2 of Fig. 1 with the ladder 40 passed out of the window and in position for use;

Fig. 3 is an enlarged view of a fragment of the ladder, and

45 Fig. 4 is a fragmentary view of one of the rungs of the ladder.

The ladder 1 which constitutes the major element of the fire escape includes side chains 2 and rungs 3, it being understood that the ladder may be of any length desired 50 and a suitable number of rungs provided in proper spaced relation to each other. The chains 2 are formed of interconnected links, each of which includes an upper eye 4 and a lower eye 5 extending longitudinally of the eye 4 but disposed transversely thereof. The 55 ends of the wire strand from which the link

is formed are bent about the intermediate portion thereof, as shown at 6, thereby forming a link which is very strong and not liable to open when strain is applied by persons 60 climbing up or down the ladder.

The rungs 3 are formed from bars which are preferably iron or steel but may be any metal desired having strength enough to prevent the rung from being bent or broken 65 when weight is applied to it. The ends of the bar or heavy rod as it may be termed are bent to form large eyes 7 which are engaged with the eyes of certain of the links from which the chains are made. These eyes 7 are of greater diameter than the eyes of the links and project from the chain at opposite sides of the rungs, as clearly shown in Fig. 2, so that when the ladder is in use 70 and a person is ascending or descending the eyes will engage the wall of the building if the ladder swings toward it and prevent the fingers from becoming mashed between the rungs and the wall and also permit the feet to be easily engaged with the rungs. In the 75 preferred construction each of the eyes 7 is formed with a notch or recess 8 to receive the eye of the chain link and cause the rung to be more readily held in the position shown in Figs. 3 and 4 with the eyes disposed horizontally and projecting from the chains, as 80 shown in Fig. 2.

At their upper or inner ends the chains 85 are engaged with strong screw eyes 9, the eyes of which are permanently closed and these screw eyes are preferably screwed into the base board 10 beneath the window 11 or if the room is not provided with a base board they may be screwed into the floor or into the window sill. The box or receptacle 12 in which the ladder is to be stored when not in use is of sufficient length to dispose the rungs 90 longitudinally therein and will, of course, be of the proper depth and width to receive a ladder of a predetermined length. The 100 ladder must, of course, be of sufficient length to permit of its being passed out of the window and suspended externally of the building with its lower end close to the ground. The receptacle may be fastened to the floor 105 by screws 13 or if so desired it may merely rest upon the floor without being secured thereto. A cover 14 is provided for the open upper end of the receptacle and this cover is preferably formed with depending flanges 110 engaging the outer faces of the walls of the receptacle to hold the cover in place,

Notches 15 are formed in one of the walls and are of sufficient depth to permit of the cover being set firmly upon the receptacle with the chains 2 extending through the 5 notches 15 into the receptacle. A suitable inscription is preferably provided upon the lid and outer wall of the receptacle calling attention to the ladder which is to be removed from the receptacle and passed out 10 of the window in case of fire. It will thus be seen that there has been provided a fire escape which is of a simple construction and at the same time very strong and durable and further so constructed that when not in 15 use it may be stored in a relatively small receptacle which will not be unsightly.

Having thus described the invention, I claim:

1. A fire escape comprising a ladder including side chains formed of interconnected links and adapted to be anchored at their upper ends to a support, and rungs extending between said chains and at their ends provided with eyes passed through certain 25 of said links, said eyes being of greater di-

ameter than the links and having their outer portions formed with internal notches adapted to receive portions of the links through which the eyes pass and effect inter-engagement of the eyes and links to prevent tilting of the rungs out of a position having their eyes disposed transversely of the chains with portions extending therefrom for engagement with a wall to hold the 30 rungs spaced from the wall. 35

2. A fire escape comprising a ladder including side chains adapted to be anchored at their upper ends to a support, said chains being formed of loosely connected links, and rungs extending between said chains, said 40 rungs being formed of metal bars having their end portions bent to form eyes engaged with certain of the links, said eyes having rearwardly projecting portions extending 45 transversely of and beyond the chains and adapted to engage the wall of a building and space the body of the rung therefrom.

In testimony whereof I affix my signature.

JOHN C. BRIGHTON. [L. s.]
